UNITED STATES PATENT OFFICE.

ALVAH E. BULLOCK AND ARTHUR BLAIN, OF MANCHESTER, NEW HAMPSHIRE.

BUILDER-MOTION FOR SPINNING OR WINDING MACHINES.

1,243,485.

Specification of Letters Patent. Patented Oct. 16, 1917.

Application filed February 26, 1917. Serial No. 150,885.

To all whom it may concern:

Be it known that we, ALVAH E. BULLOCK and ARTHUR BLAIN, citizens of the United States, residing at Manchester, county of Hillsborough, and State of New Hampshire, have invented an Improvement in Builder-Motions for Spinning or Winding Machines, of which the following description, in connection with the accompanying drawings, 10 is a specification, like characters on the drawings representing like parts.

The invention to be hereinafter described relates to yarn spinning or winding machines, and more particularly to the means 15 whereby a "bunch" may be produced upon the bobbin or bobbins during the spinning or winding operation.

In laying or winding the yarn upon bobbins for subsequent use in the loom, it is 20 sometimes desirable to provide a few preliminary windings on the bobbins before commencing the regular or service wind. These preliminary windings are generally known in the art as a "bunch," and bobbins so 25 wound are employed in "feeler" looms to insure that the last pick laid prior to replenishment of filling shall extend the full width of the cloth. In some feeler looms the bunch may coact with the feeler mechanism, but, so far as the present invention 30 is concerned, these matters are immaterial.

The "bunch" should be laid by a different traverse of the yarn from that of the regular or service wind, and upon completion 35 of the bunch it is desirable that the traverse of the regular or service wind shall be automatically resumed. It is also important that the traverse for the bunch be made effective when the spinning or winding 40 operation is started, and with these generally-stated facts in view, an important feature of the present invention consists in means between the builder motion and 45 yarn guiding devices for effecting a short traverse of the yarn during the building of the bunch and automatically acting when the bunch is completed to cause the yarn to be laid in the regular or service traverse.

Another important feature of the invention 50 consists of a pulley or drum and cam member between the builder motion and yarn guiding means which are locked together during the bunch-building operation and upon the completion of the bunch are 55 unlocked. Still another important feature of the present invention consists of a pulley

or drum and a cam member having separate connections with the yarn guiding means and yieldingly held in locked relation during the bunch-building operation, and then 60 relatively moved against the action of the yielding means to unlock the pulley or drum and cam member when the bunch has been completed that the regular traverse may be resumed.

Other features of the invention, in addition to the above, will be hereinafter described in connection with the accompanying drawing showing a good, practical form thereof, it being understood that details may 70 be varied within the true scope of the invention as definitely set forth by the claims.

The invention is herein illustrated as employed in connection with a ring-spinning machine, and while it is particularly well 75 adapted to this type of machine, it is to be understood that it may be employed with advantage in other types of spinning or winding machines.

In the drawing:—
Figure 1 is a front elevation showing a portion at one end of a ring-spinning machine, having the present invention associated therewith;

Fig. 2 is an enlarged side elevation showing the pulley or drum and cam member, and their connected parts in the relations assumed at the commencement of the winding operation;

Fig. 3 is a view similar to that of Fig. 2, 85 showing the relation of parts after the bunch has been formed and during the regular or service traverse;

Fig. 4 is an edge view of the pulley or drum, the cam member, and the means for locking them in the relation shown by Fig. 2; and

Fig. 5 is a detached detail showing the means for unlocking the cam member and pulley or drum.

The machine frame for supporting the operative parts may be of any usual construction, and as typified in the present illustrated form of the invention, is of the usual type of the ring-spinning frame and comprises the end frames 1 connected by the longitudinal rails 2. Mounted on the spindle rail 3 are a series of spindles 4, provided with pulleys or whirls 5 by which the spindles may be driven as usual, from 110 any suitable source of power. The spindles 4 extend upwardly through the ring-rail

6 which carries the rings 7 on which are mounted the usual travelers for directing or guiding the yarn to the bobbins 8 mounted on the spindles 4.

5 Extending downwardly from the longitudinal rail 2 is the bracket 9 having pivotally mounted thereon at 10 the lifter arm 11 carrying the usual counter weight 12. Resting upon the end of the lifter arm 11 10 is the foot 13 of the lifter rods 14, a roll or pin 15 being employed, if desired, upon which the foot 13 may rest. The ring-rail 6 may extend an indefinite distance longitudinally of the frame and have extending 15 downwardly therefrom a series of lifters 14 for co-operation with the other lifting arms, as usual in this class of machines; and in order that such lifter arms may operate in unison, the lifter arm 11 is provided with 20 the upwardly-extending arm 16 to which is connected one end of a rod 17 for joining the several lifter arms, as usual.

25 Adjustably secured to the arm 16 is the extension or arm 18, adjustment being effected by any suitable means such, for instance, as the bolt 19 passing through the arm 16 and the slotted lower portion of the arm 18. The arm 18 carries the block 20, Fig. 1, to 30 which are secured the ends of the connections leading from the pulley or drum and the cam member, as will presently appear.

35 The builder motion proper may be of any usual or desired character, and as shown, comprises the usual builder arm 21 pivoted at 22 to the brackets 23 and 24 which may extend from the machine frame, as indicated. The builder arm carries the usual projection or pin 25 which bears upon the periphery of the builder cam 26 mounted 40 on the shaft 27 properly supported upon the machine frame, as indicated, and driven from any suitable source of power. In the present instance of the invention, the shaft 27 has the bevel gear 28 secured thereto, 45 which meshes with a bevel pinion 29 secured to the operating shaft 30, the construction being such that upon rotation of the operating shaft 30, the builder cam 26 will be rotated, as usual in this class of machines, 50 for operating the builder arm, as well understood by those skilled in the art. The builder arm carries the unwinding drum 31 which is slowly turned by means of the usual worm 32 and pick-wheel 33 which is actuated 55 by the pick pawl 34 in a manner well understood by those skilled in the art, the construction being such that as the builder arm rises and falls under the control of the cam 26, the unwinding drum 31 will be rotated step-by-step through the pick-wheel 60 and pick-pawl, for giving back on the flexible connection 35 which connects the unwinding drum 31 to the pulley or drum 36.

65 Loosely mounted on a fixed stud 37 is the pulley or drum 36 which is joined by the

flexible connection or chain 35 with the unwinding drum 31. The pulley or drum 36 is also connected to the yarn guiding means so that as the pulley or drum 36 is rotated or rocked on its fixed bearing 37, 70 the yarn guiding means will be raised by the weight 12 of the lifter arm and depressed or pulled downward by the connection 35 with the builder motion. In the present form of the invention, the pulley or drum 36 75 has secured to it at 38 the chain or other form of flexible connection 39, the other end of which is secured at 40 to the arm 18 extending from the lifter arm 11.

Also loosely mounted upon the fixed stud 80 37 is the cam member 41 having the slabbed-off portion 42 and secured to the cam member at 43 is the chain or other flexible connection 44 which is jointed at 40 to the arm 18, the construction being such that the arm 85 18 and, perforce, the lifter arm 11 and yarn guiding means, are under the control of the two connections 39 and 44, one leading from the pulley or drum 36 and the other from the cam member 41.

90 The cam member 41 is provided with a locking device for locking it to the pulley or cam 36 at times, as will presently appear, and in the present instance of the invention, said locking device consists of a pin 45 extending through the cam member 41 and threaded therein substantially as indicated in Fig. 5. A set nut 46 may be employed for holding the locking device or pin 45 in its adjusted position. The face of the pulley or drum 36 is provided with a recess 47 and a flattened raised portion 48, against the edge 49 of which the locking device or pin 45 is adapted to bear when the parts are in the position indicated in Fig. 2, that is, at 100 the commencement of the building operation, at which time the flexible connection 44 leading from the cam member 41 passes over the slabbed-off portion 42 of the cam member, the construction being such that as the 105 builder arm rises under the dictates of the cam 26, and lets back on the pulley or drum 36, the cam member 41 follows the pulley or drum 36 and controls the lifting action of the ring-rail 6. Since, during this backward movement of the pulley or drum 36, 110 the flexible connection 44 leads over the slabbed-off portion of the cam member 41, the ring-rail will be lifted by the weight 12 a less distance than it would be lifted were 120 the ring-rail under the control of the flexible connection 39 alone, so that the initial winding under the conditions stated, will be of a shorter traverse than the regular or service traverse.

125 The cam member 41 in addition to being loosely mounted upon the fixed stud 37, is movable longitudinally on said stud toward and from the pulley or drum 36, and in order to maintain the cam member 41 nor-

5 mally pressed toward the pulley or drum 36, yielding means are provided. In the present form of the invention this yielding means comprises a spring 50, one end 51 of which is received in an opening formed in a collar 52 secured to the stud 37 by means such as the set screw 53, and the other end of said spring is secured by suitable means such as the screw 54, to the cam member 41, the construction being such that while the 10 spring 50 may exert expansive force against the cam member 41 to force the cam member yieldingly toward the pulley or drum 36, it will, nevertheless, yield to permit the cam member to move longitudinally of the stud 37 away from the pulley or drum 36 to thereby unlock the cam member 41 from the pulley or drum 36.

20 Various means for causing relative movement of the pulley or drum 36 and the cam member 41 toward and away from each other may be devised within the scope of the invention, but in the present instance thereof, the stud 37 has secured thereto and rising 25 therefrom, a fixed pin 55, Figs. 4 and 5, and the hub portion of the cam member 41 has a recess 56, the walls of which are beveled or inclined as at 57, Fig. 5, the construction being such that should the cam member 41 30 be moved clockwise, viewing Fig. 2, to cause the beveled or inclined surface 57 to ride over the fixed pin 55, the cam member 41 will be moved longitudinally on the fixed stud 37 away from the pulley or drum 36 to 35 thereby disengage the locking device 45 from the shoulder 49 of the pulley or drum.

40 At the commencement of the winding operation, the parts are in the position indicated by Fig. 2, with the cam member and pulley or drum in locked relation, that is, with the pin 45 bearing against the shoulder 49 of the pulley or drum. As the builder arm lets back on the flexible connection 35, the pulley or drum 36 and perforce, the cam 45 member 41, will turn clockwise, Fig. 2; and since the flexible connection 44 leads from the slabbed-off portion of the cam member, it will control the rising movement of the ring-rail and give a short traverse to the 50 yarn longitudinally of the bobbins, the connection 39 between the pulley or drum 36 and the ring-rail becoming slack. On each successive upward movement of the builder arm, the let-back action of the flexible connection 35 becomes greater and greater due to the let-off drum 31, until, when the bunch has been completed, the beveled or inclined surface 57 of the cam member 41 will meet the fixed pin 55 and force the cam member 55 longitudinally away from the pulley or drum 36, thereby unlocking the pulley or drum and the cam member, and the end of the pin 45 will rest upon the surface 48 of the pulley or drum 36, owing to the pull of 60 the flexible connection 44. Thus, during the

bunch-building operation, the cam member 41 and the pulley or drum 36 are locked in operative relation, and when the bunch has been completed with the desired number of short traverses, the cam member and pulley 70 or drum will be automatically unlocked and will remain in unlocked position to permit the ring-rail to remain under the control of the flexible connection 39 between the drum and the ring-rail during the remainder of 75 the regular or service traverse.

When the bobbins have been completely wound and doffed and the flexible connection 35 is again wound upon the drum 31, preparatory to the commencement of the 80 winding operation, it is desirable that the cam member 41 and the pulley or drum 36 resume their locked condition as indicated in Fig. 2. To this end, the spring 50 has in addition to its expansive action for holding 85 the cam member 41 in locked relation with the pulley or drum 36, a torsional action, the construction being such that when the flexible connection 35 is wound upon the drum 31, the flexible connection 44 becomes slack 90 and the spring 50 asserts its torsional action to return the cam member 41 into position for engagement of the locking pin 45 back of the shoulder 49 of the pulley or drum 36, and the parts are in position to resume or 95 commence the winding operation.

The construction above described has been found to be a good, practical form of the invention; but it is to be understood that the particular character of the locking device 100 and the particulars of the means for unlocking the cam member and the pulley or drum when the bunch has been completed, may be variously contrived within the true scope of the actual invention as defined by the claims. 105

What is claimed is:—

1. In a spinning or winding machine, the combination of a builder motion, guiding means for directing the yarn to the bobbins, a pulley or drum, a cam member, means for 110 detachably connecting the cam member and drum together that movement of the cam member may be controlled by the pulley or drum during the building of the bunch, a flexible connection between the builder motion and drum and between the drum and guiding means, a flexible connection between the cam member and guiding means for building a bunch, and means for automatically disconnecting the cam member from 115 the drum on completion of the bunch.

2. In a spinning or winding machine, the combination of a builder motion, guiding means for directing the yarn to the bobbins, a loosely mounted pulley or drum, a loosely 120 mounted cam member, a flexible connection between the builder motion and guiding means secured to the pulley or drum, a flexible connection between the cam member and guiding means, means for operatively con- 125

necting the pulley or drum and cam member together that the movement of the cam member may be controlled by the pulley or drum during the building of the bunch with relatively short traverse, and means for automatically disconnecting the pulley or drum and the cam member when the bunch is completed.

3. In a machine of the character described, 10 the combination of a builder motion and ring-rail, a pulley or drum, a flexible connection between the builder motion and ring-rail operating said drum during regular traverse, a slabbed-off cam member and flexible connection between it and the 15 ring-rail, means for operatively connecting the pulley or drum and cam member to cause movements of the cam member to be controlled by the pulley or drum until a 20 bunch has been formed of relatively short traverse, and means for automatically disconnecting the pulley or drum and cam member after the bunch has been completed.

4. In a machine of the class described, the 25 combination of a builder motion and ring-rail, a pulley or drum, a flexible connection between the builder motion and ring-rail operating said drum during regular traverse, a cam member, a flexible connection between 30 the cam member and ring-rail, means acting yieldingly to hold the pulley or drum and cam member operatively connected that the cam member movements may be controlled by the pulley or drum during the building 35 of a bunch, and means acting automatically to disconnect the pulley or drum and cam member when the bunch is completed.

5. In a machine of the general character 40 described, the combination of a builder motion and yarn guiding means, a drum or pulley, a flexible connection between the builder motion, the drum or pulley, and the 45 yarn guiding means, a cam member, a flexible connection between the yarn guiding means and the cam member passing over the slabbed-off portion of the cam member at the commencement of the winding operation, means carried by the cam member and engaging the pulley or drum to cause them 50 to move in unison during the bunch-building operation, and means acting automatically to relatively move the pulley or drum and cam member in a direction of separation to operatively disconnect the pulley or 55 drum and cam member when the bunch is completed.

6. In a machine of the character described, 60 the combination of a builder motion, yarn guiding means, connections between the builder motion and yarn guiding means including a pulley, a cam member, flexible 65 means between and connecting the cam member and yarn guiding means, a spring normally acting to maintain the cam member and pulley for movement in unison dur-

ing the bunch building operation, and means for freeing the cam member from connection with the pulley when the bunch has been wound.

7. A bunch builder for spinning or winding machines, comprising a builder motion, 70 yarn guiding means, a pulley, a flexible connection between the builder motion and yarn guiding means engaging said pulley and operating the latter as the guiding means is given its traverse movement, a cam member, a flexible connection between the cam member and yarn guiding means, a locking device for locking the cam member and pulley together during the building of 80 the bunch, and means for tripping the locking device to free the cam member from the pulley when the bunch has been completed and service traverse is to be resumed.

8. A bunch builder for spinning or winding machines, comprising a builder motion, 85 yarn guiding means, a pulley, a flexible connection between the builder motion and yarn guiding means engaging said pulley and operating the latter as the guiding means is given its traverse movement, a cam member, a flexible connection between the cam member and yarn guiding means, a locking device for locking the cam member and pulley together during the building of 90 the bunch, and means for moving the cam member in an axial direction away from the pulley to free the locking connection with the pulley when the bunch has been completed. 100

9. In a machine of the character described, the combination of a builder motion, yarn guiding means, a pulley, a stud on which the pulley is rotatably mounted, a flexible connection between the builder motion and yarn guiding means, a cam member mounted for rotative and longitudinal movement on said stud, a flexible connection between the cam member and yarn guiding means, means normally acting to force the cam member 105 longitudinally of said stud into operative engagement with the pulley, and means for moving the cam member longitudinally in the opposite direction out of operative engagement with the pulley when the bunch 110 has been completed and service traverse is to be resumed. 115

10. In a machine of the character described, the combination of a builder motion, yarn guiding means, a pulley, a stud on which 120 the pulley is rotatably mounted, a flexible connection between the builder motion and yarn guiding means, a cam member mounted for rotative and longitudinal movement on said stud, a flexible connection between 125 the cam member and yarn guiding means, means normally acting to force the cam member longitudinally of said stud into operative engagement with the pulley, and a fixed pin or abutment, said cam member 130

having an inclined portion to engage the pin or abutment to move the cam member longitudinally of the stud out of operative engagement with the pulley when the bunch 5 has been completed.

11. In a machine of the character described, the combination of a builder motion, yarn guiding means, a pulley mounted for rotative movement, a flexible connection between 10 the builder motion and yarn guiding means operating said pulley, a cam member mounted for rotative movement and also for movement toward and from the pulley, a spring acting normally to move the cam member

toward the pulley into operative relation 15 therewith during the building of the bunch with a relative short traverse, means for automatically moving the cam member away from the pulley out of operative relation thereto when the bunch has been formed 20 and service traverse is to be resumed, and a flexible connection between the cam member and yarn guiding means.

In testimony whereof, we have signed our names to this specification.

ALVAH E. BULLOCK.
ARTHUR BLAIN.
